(57) **CLAIM**

The ornamental design for a wraparound shaped duffle bag, as shown and described.

DESCRIPTION

FIG. 1 is a top view of a wraparound shaped duffle bag showing the detachable shoulder strap attached.

FIG. 2 is a perspective view of the inner side of the wrap-around shaped duffle bag shown with the shoulder strap detached.

FIG. 3 is a perspective view thereof, showing the top and the right end.

FIG. 4 is a perspective view thereof, showing the top and the outer side; and,

FIG. 5 is a perspective view similar to FIG. 4, but with the outer wall folded in a compressed position.

1 Claim, 3 Drawing Sheets

FIG. 1

FIG. 2

FIG. 3

FIG. 4

FIG. 5
